UNITED STATES PATENT OFFICE.

JOHN E. PARKISON, OF SEATTLE, WASHINGTON.

DENTAL CASTING MACHINE.

Application filed October 22, 1923. Serial No. 670,169.

To all whom it may concern:

Be it known that I, JOHN E. PARKISON, a citizen of the United States, and resident of Seattle, county of King, State of Washington, have invented certain new and useful Improvements in Dental Casting Machines, of which the following is a specification.

This invention relates to dental casting machines of the type in which compressed air is employed for forcing the molten metal into the mold.

The object of the invention is to provide a machine of this kind in which the cap or cover for the mold flask may first be forced against the flask with any desired amount of pressure so as to make a perfectly tight joint and the compressed air then admitted to the flask. More specifically, the invention aims to provide a construction in which a cap or cover for the flask is carried by a suitable support on which is pivotally mounted a suitable plate or handrest by which the cap may be pressed against the flask and which may be tilted about its pivot point to admit compressed air to the flask. A further object is to provide an arrangement in which the cap is adjustable relative to the support and capable of being clamped in any desired position to accommodate flasks of different heights. A still further object is to provide a machine which is simple and compact in construction and convenient in operation, requiring little space for its use, and one in which the parts are so arranged that the compressed air is compelled to travel only a short distance from the control valve to the casting flask so that the air can be quickly applied to the molten metal in the flask before the same can cool appreciably.

In the drawings:

Figure 1 is a plan view of my improved machine,

Figure 2 is a longitudinal vertical section of the same substantially on the line 2-2 of Figure 1,

Figure 3 is a longitudinal horizontal section of a part of the machine taken on the line 3-3 of Figure 2,

Figure 4 is a transverse vertical section on the line 4-4 of Figure 2.

Referring to the drawings in detail, the numeral 10 represents the base or body of the machine. At one end of the base 10 I provide a compressed air chamber 11 having

a suitable air gauge 11^a and an opening 11^b through which air may be supplied. At the other end of the base I provide a platform 12, upon which a flask A is adapted to rest, such flask containing the usual material B in which the mold is formed, and also the ordinary depression C for containing the molten metal to be forced into the mold. The platform 12 is preferably provided with a series of lugs or projections 13 which form centering means for a plate such as 14, which is loosely placed on the platform and which is provided with a central opening for receiving the flask whereby it is accurately centered on the platform. A series of centering plates such as 14 is preferably provided having different sized central openings to accommodate flasks of different diameter.

My improved machine is provided with a cap or cover 15 which is adapted to be forced down upon the flask placed upon the platform 12, the cap being preferably provided with a disk 16 of moistened fiber or other suitable material. The cap 15 is rigidly and preferably integrally connected with a valve casing 17, and these parts are carried by a suitable support by which the same may be moved toward and from a flask resting on the platform. Preferably such support comprises spaced arms or members 18 between which the casing 17 is arranged. These arms are preferably integrally connected at their front ends, and at their rear ends they are pivotally connected to the air chamber 11 by means of a pivot rod 18^a which extends through openings in the arms and in lugs 18^b formed on said chamber. Between the inner surfaces of the arms 18 and the lugs 18^b, I arrange friction washers 18^c of leather or other suitable material, and a thumb nut 18^d on the rod 18 can be adjusted to produce sufficient friction between said washers and the adjacent parts to hold the arms 18 and the parts attached thereto in any position to which they are moved. Each of said arms 18 near its rear end is provided with a stop lug 18^e which is adapted to contact with the rear wall of the chamber 11 to limit the upward pivotal movement of the arms 18 and hold the same in raised position.

The combined cap 15 and casing 17 is adjustably connected to the arms 18 through the medium of lugs 20 integral with the cap and which are engaged by screws 21 extending through the arms and into openings in

said lugs. One or both of said screws may be provided with wings 21^a by which the same may be tightened so that the combined casing and cap can be clamped in rigid relation to the support formed by the arms 18.

The casing 17 is provided with an air passage 22 which communicates through the medium of a flexible pipe 23 with the compressed air chamber 11. This air passage 22 communicates with a passage 22^a extending through the cap 15 so that compressed air may flow through said passages and into a flask upon which the cap is placed. The air passage 22 is controlled by a valve 24 which is held to its seat by a coiled spring 25 arranged within the casing 17 and positioned between the valve and a screw plug 26 threaded into the rear end of the casing. A stem 27 secured to the valve 24 extends through a plug 28 threaded into the front end of the casing and forming a stuffing box preventing escape of air around the stem. It will be apparent that when the valve 24 is opened compressed air may flow through the passages 22 and 22^a and into a flask placed beneath the cap 15.

To provide means for manually pressing the cap 15 against a crucible and for opening the valve 26, a member 30 is pivotally connected to the arms 18 of the support, this pivotal connection being effected by means of lugs 31 integral with the member 30 and ears 32 extending upwardly from the arms 18, a pivot pin 33 extending through aligned openings in said lugs and ears. The upper portion of the member 30 is shaped to provide a substantially flat hand rest 30^a so shaped that the hand of the operator may be conveniently placed upon the same for forcing the parts downwardly toward the platform 12. On the under side of the member 30 there are rigidly secured downwardly projecting arms 34, the lower ends of which engage the rear ends of a bale 35, which bale extends forwardly and across the front end of the casing 17. This bale is adapted to contact with and move the stem 27 of the valve 24. To hold the bale in proper position to contact with the stem there is provided a guide plate 36 having notched ends through which the bale 35 passes, the intermediate portion of this plate being provided with an opening through which the stem 27 of the valve extends. It will be understood that when the member 30 is moved about its pivotal connection with the arms 18, the arms 34 connected therewith will draw the bale 35 rearwardly, thus forcing the stem of the valve 27 into the casing and opening the valve. The spring 25 serves to close the valve 26 and to restore the parts to their original position when pressure on the member 30 is relieved.

Briefly describing the operation of the device, it will be understood that a flask of

the particular size which it is desired to use for making a casting is first placed on the platform 12. The cap 15 is then brought down firmly upon the upper edge of the crucible, the screws 21 being loosened to permit the cap to take a position in which it will accurately fit against the upper edge of the flask. One or both of the screws 21 is then tightened which rigidly locks the cap 15 and the casing to the supporting member formed by the arms 18. It will thus be apparent that in using crucibles of different size and height, which is necessary in dental work, the cap 15 can always be adjusted and locked so that it will accurately fit the top of the crucible when it is pressed down upon the same preparatory to admitting the compressed air. After the cap has thus been locked in proper position and the crucible with the molten metal therein is placed on the platform 12 and the cap brought down upon the crucible, the operator by pressing down upon the hand rest 30^a may force the cap with any desired pressure into close engagement with the upper end of the crucible so as to obviate all danger of escape of compressed air. After the desired pressure of the cap against the crucible is obtained, by simply moving the hand so as to tilt the member 30 on its pivot, the arms 34 connected to this member will draw the bale 35 rearwardly against the stem 27 of the valve 26 and open the same whereupon compressed air will flow through the passages 22 and 22^a, and into the crucible. Of course, the operations of pressing the cap against the flask and tilting the member 30 may be performed substantially simultaneously, that is, the downward pressure on the member 30 may be so applied as to press the cap against the flask and at the same time automatically tilt this member to open the valve 26. Preferably the spring 25 is made sufficiently strong so that when the support is forced downwardly by pressure on the member 30 in front of its pivot point, the spring will offer sufficient resistance to cause the cap to be forced tightly against the flask before the member 30 tilts and opens the valve 26. After the casting operation is completed, and the hand of the operator is removed from the member 30, the spring 26 will again force the valve to its seat and through the medium of the stem 27, bale 35 and arms 34, the parts will be returned to normal position. The friction washers 18^a serve to hold the arms in any position to which they are moved so that in using the machine it is not necessary to always lift the arms to their limit when inserting or removing a flask.

It will be noted that by arranging the compressed air chamber between the arms 18, it is possible to provide a very compact and convenient arrangement, since all the parts

are contained in little space and the device can be used where little room is available. Furthermore, by making the platform and air chamber integral, a very rigid construction is produced, which is easy and economical to manufacture.

Various changes in the details of the foregoing construction obviously may be made without departing from the spirit or principle of the invention.

Having thus described the invention what is claimed as new and desired to be secured by Letters Patent is:

1. In a casting machine, in combination, a cap adapted to rest on a casting flask and having a passage for compressed air, a movable support for said cap, a valve casing having a passage communicating with said first named passage, a valve in said casing, a member carried by and movable with said support and forming means for pressing said cap against a flask, said member also being movable relative to said support, and means operated by the movement of said member relative to said support for moving said valve.

2. In a casting machine, in combination, a casing having an air passage therein, a valve in said casing for controlling flow of air through said passage, a cap carried by said casing and adapted to rest on a flask, said cap having a passage communicating with said first named passage, a movable support for said casing and cap, a member carried by and movable with said support and forming means for pressing said cap against a flask, said member also being movable relative to said support, and means operated by such relative movement of said member for moving said valve.

3. In a casting machine, in combination, a casing having an air passage therein, a valve in said casing for controlling flow of air through said passage, a cap connected to said casing and adapted to rest on a flask, said cap having an air passage communicating with said first named passage, a movable support for said cap, a hand rest tiltingly mounted on said support and forming means for pressing said cap against a flask, and means operated by tilting movement of said hand rest relative to said support for moving said valve.

4. In a casting machine, in combination, a casing having an air passage therein, a valve in said air passage, a cap carried by said casing and adapted to rest on a flask, said cap having a passage communicating with said first named passage, a movable support for said casing and cap, a member mounted on and supported wholly by said support and forming means for pressing said cap against a flask, said member being pivotally connected to said support and means operated by pivotal movement of said

member relative to said support for moving said valve.

5. In a casting machine, in combination, a base having a chamber for compressed air, a support pivotally connected to said base, 70 a casing carried by said support and having an air passage, a pipe connecting said passage with said chamber, a valve in said casing for controlling said passage, a cap carried by said casing and adapted to rest 75 against a flask, said cap having a passage communicating with said first named passage, a member tiltingly mounted on said support and forming means for pressing said cap against a flask, and means operated by the tilting of said member relative to said support for moving said valve.

6. In a casting machine, in combination, a valve casing, a movable support therefor, a cap connected to said casing and adapted 80 to be forced against a flask by movement of said support, said casing and cap having an air passage therein, a valve in said casing for controlling said passage, a member carried by said support and pivotally connected 85 thereto, said member forming means by which said cap may be forced against a flask without moving the member about its pivotal connection with said support, and means operated by pivotal movement of said 90 member relative to said support for moving said valve.

7. In a casting machine, in combination, a valve casing, a cap carried thereby, a movable support on which said casing is 100 mounted, said casing and cap having an air passage therein, a valve in said casing for controlling said passage, a lever pivotally connected to said casing, one portion of said lever being shaped to provide a hand rest by which said cap may be forced against a flask without movement of the lever about its pivot, and means operated by pivotal movement of said lever relative to the support for moving said valve.

8. In a casting machine, in combination, a valve casing, a cap carried thereby, a movable support on which said casing is mounted, said casing and cap having an air passage therein, a valve in said casing for controlling said passage, said valve having a stem extending outside of said casing, a member pivotally connected to said support and forming means for manually forcing said cap against a crucible, and means operated by pivotal movement of said member relative to the support for moving said valve stem to operate said valve.

9. In a casting machine, in combination, a valve casing, a cap carried thereby, a movable support on which said casing is mounted, said casing and cap having an air passage therein, a valve in said casing for controlling said passage, a member pivotally connected to said support and having a por-

tion arranged above said casing and a hand rest by which said cap may be manually forced against a crucible without movement of said member relative to said support, said member also having an arm below said first named portion, and means operated by said arm for opening said valve when said member is moved relative to said support.

10. In a casting machine, in combination, a valve casing, a cap carried thereby, a movable support on which said casing is mounted, said casing and cap having an air passage therein, a valve in said casing for controlling said passage, a member pivotally connected to said support and having a substantially flat portion arranged above said casing and forming a hand rest by which said cap may be forced against a crucible, said member also having arms extending downwardly from said flat portion on opposite sides of said casing, and means operated by said arms for opening said valve when said member is moved about its pivotal connection with said support.

11. In a casting machine, in combination, a cap adapted to contact with a casting flask and having a passage for compressed air, a movable support for said cap, said cap being adjustable relative to said support, means for clamping said cap to the support in any desired position of adjustment, a valve casing rigid with said cap having a passage communicating with said first named passage, a valve in said casing, and means carried by said support for operating said valve.

12. In a casting machine, in combination, a base, a valve casing, a support for the same pivotally connected to said base, a cap rigid with said casing, said casing and cap being adjustable relative to said support, means for clamping said cap and casing to said support in any desired position of adjustment, a valve in said casing, and means carried by said support for opening said valve to permit compressed air to flow through said casing and cap.

13. In a casting machine, in combination,

a base, a support pivotally connected thereto, a valve casing carried by said support, a valve in said casing, a cap rigidly secured to said casing, said cap and casing being adjustably connected to said support, means for clamping said cap and casing to the support in any desired position of adjustment, a member carried by said support and forming means for pressing said cap against a flask, said member being pivotally connected to the support, and means operated by pivotal movement of said member relative to the support for moving said valve.

14. In a casting machine, in combination, a base having at one end a platform for holding a flask and at the other end a chamber for compressed air, arms pivotally connected to the last named end of the base, a cap carried by said arms and adapted to be brought into contact with a flask on said platform, a valve casing connected to said cap, a valve in said casing, said cap and casing having a passage for compressed air, a flexible conduit for conducting compressed air from said chamber to said passage, a member carried by said arms and forming means for pressing said cap against a flask, said member being pivotally connected to said arms, and means operated by movement of said member relative to said arms for moving said valve.

15. In a casting machine, in combination, a base, arms pivotally connected thereto, a cap carried by said arms, a valve casing connected to said cap, a valve in said casing, a member pivotally connected to said arms and forming means for pressing said cap against a flask, means operated by pivotal movement of said member relative to said arms for moving said valve, and friction means arranged at the pivotal connection between said base and arms for holding the latter in any position to which they are moved.

In testimony whereof I hereunto affix my signature.

JOHN E. PARKISON.
